ADVERTISING SIGN DEVICE

Joseph Popper, deceased, late of Brooklyn, N. Y.,
by Ruby H. Popper, administratrix, Brooklyn,
N. Y.

Application July 28, 1943, Serial No. 496,677

1 Claim. (Cl. 40—126)

This invention relates to improvements in advertising devices, such as a display sign or advertising card which may be mounted on a suitable frame or rack within a street car, bus, subway car or other public vehicle.

An object of the invention is to provide a display sign having certain movable parts thereon, the movement of said parts being made to simulate a wave formation or a series of wave ripples of a liquid within a view opening shown in connection with the picture of a transparent bottle or like container and operated by vibration of the vehicle.

A further object of the invention is to provide an advertising sign having mounted thereon a series or plurality of wave riplet members that are automatically movable in overlapping relation with each other, said movement requiring no supplemental power or impelling means beyond that of the movement or vibration of the vehicle itself to which said sign is mounted.

A further object of the invention is to provide for the applicability thereof to a movable or slideable object, such as, display engines, automobiles, trucks, movable doors, windows or other moving objects, including steamships.

With the foregoing and other objects in view, the nature and features thereof will be more readily understood by the following description and the drawing accompanying the same, in which—

Fig. 1 illustrates a display sign having a picture or representation of a bottle or like container, said bottle displaying to view a series of vibrating members mounted in the front of the bottle in the picture.

Fig. 2 is an elevational view of the bottle picture showing in detail the vibrating members and their manner of mounting.

Fig. 3 is a side sectional view of the display sign on a line 3—3 of Fig. 2.

Fig. 4 is an elevational view showing a single vibrating or liquid-level-wavelet member, the wave motion of which is shown in dotted lines.

Referring to the drawing, the designation 10 shows the picture of a bottle placed on a slight angle, and 11 are the vibrating members which are partially shown in the transparent view opening or section 12 of the bottle. The picture 10 may be made on a panel or card 13 bearing the picture of the bottle or other container for a liquid.

There is provided a lower neck portion 11^a for each of the members 11. These neck portions 11^a are mounted upon flexible or springy wires

11^b and said resilient wires are mounted by means of screws 11^c onto the rear portion of an enclosing wall 14 attached at the rear of said display sign or card 13. The wall 14 is not in view when observing the front of the display sign and forms a protective enclosure for the vibrating members 11.

We are assuming the picture of the bottle is represented as being normally filled to and within the view opening 12, where the level of the simulated liquid is observable and where the tops of the vibrating members are visible to indicate the liquid level. The vibration or movement of the members 11 not only move from side to side, but also have a certain amount of vertical or bobbing movement which is due to the curved or L-shape of the spring wire or coiled spring 11^b, said curved shape being shown by the bend of the wire at 11^d.

20 The vibrating members 11 mounted in this manner, when subjected to the vibrating or moving influence heretofore explained, swing sideways and also bob lengthways giving the overall or composite appearance of wavelets on the top of the simulated liquid level of the bottle.

The spring wire 11^b may be a closed coil spring which permits of greater flexibility and sensitiveness to vibration impulses.

It will be seen that the method of mounting 30 the individual wavelet members 11 places them in overlapping relation with respect to each other at the visible portions thereof and when viewed from the front of the bottle picture.

The view opening 12 forms a transparent or 35 open portion or space in the card 13 bearing the picture 10 of the transparent container. This view opening 12 is disposed across the upper portion of the bottle, in registry with the location of the upper liquid level to illustrate the bottle as being normally filled, and extends across the width of the container picture 10 in order to show the entire surface of the liquid level. The several vibrating wavelet members 11 are disposed in lateral alignment within the one view opening 12.

The vibrating members 11 are of curved arcuate form along their upper edges to simulate the undulation or wave shape of the liquid in surface riplet form, the upper edges being disposed below 50 the top line representing the view opening 12, while the bottom edges are disposed below the lower line forming the view opening and thus hidden behind the card 13. Furthermore, the wavelet members 11 are arranged in tandem or alignment, one following the other within sub-

stantially the same or closely spaced and parallel adjacent planes. The several wavelet members are disposed within the single view opening 12 so that a number of liquid waves or undulations are represented by the overlapping upright edges in conjunction with the aligned arrangement of the thin vibrating parts 11 extending across the view opening.

At the center of the bottle picture there will be seen the wavelet member 11^T in a somewhat elevated position above the front row of the companion members 11, and the spring portion 11^b of said member 11^T being somewhat longer in length as compared with the companion vibrating spring members 11. The purpose of the latter member 11^T is to give a heightened and depth effect by the movement of all the vibrating members when the sign is subjected to the vibration of an object such as a moving vehicle to which said sign is attached.

It will therefore be seen from the herein disclosure of the invention that an advertising display device of interesting and pleasing appearance is provided and one which will compel attention. Furthermore, the device embodying the invention is easy of construction and inexpensive to manufacture.

This invention is presented to fill the need for a useful advertising sign device. Various modifications in construction, mode of operation, use and method, may and often do occur to others, especially so after they have benefited from the teachings of an invention. Accordingly, this disclosure is exemplary of the principles and equivalents without being limited to the present showing of the invention.

What is claimed is:

An advertising sign device comprising a panel bearing a picture symbolic of a container shown as holding liquid, a view opening formed in the upper portion of the panel and container picture in registry with the normal level of the liquid, a plurality of thin sheet form wavelet members operatively mounted on the sign device behind the view opening, the wavelet members having upright edges disposed in tandem relation and in closely spaced parallel planes and also in overlapping arrangement with each other, the wavelet members also being formed with upper arcuate edges which merge with each other by reason of said overlapping arrangement and which thus simulate the liquid level as having an undulated wave formation, the upper arcuate edges of the wavelet members being disposed below the top line of the view opening, while the lower edges of said wavelet members are disposed below the lower line of said view opening, and resilient means mounting each arcuate wavelet member separately on the sign device, whereby any vibration of the panel bearing the picture is imparted to each wavelet member through its separate resilient mounting means to separately actuate simultaneously the several wavelet members which thereby simulate a natural wave motion by the action of the several arcuate edges discernible through the view opening.
